WILLIAM VOGEL, OF NORWICH, CONNECTICUT, ASSIGNOR TO EZRA DURAND.

Letters Patent No. 84,027, dated November 10, 1868.

IMPROVEMENT IN MUSICAL INSTRUMENTS.

The Schedule referred to in these Letters Patent and making part of the same.

To all whom it may concern:

Be it known that I, WILLIAM VOGEL, of Norwich, in the county of New London, and State of Connecticut, have invented a new and useful Improvement in Musical Instruments; and I do hereby declare that the following is a full, clear, and exact description thereof, which will enable those skilled in the art to make and use the same, reference being had to the accompanying drawings, forming part of this specification.

This invention relates to that class of musical instruments known as the "dulcimer," and in which suitable strings or wires are held stretched over a sound-board, suitably secured within a case, in a similar manner to that employed in piano-fortes, these strings being played upon and sounded by means of hammers in the hands of the player.

This invention consists—

First, in connecting the iron bridges, on which the strings rest, near their ends, by means of cross-bars or rails passing under and below the sound-board, whereby they are stiffened and given great strength to resist the strain and tension to the strings.

Second, in so forming the brace-bars or rails upon the under side of the board as to leave an open and free communication and escape of the sound therefrom.

In the accompanying plate of drawings, my improvements in dulcimers are illustrated,

Figure 1 being a plan view of the under side of the case-box;

Figure 2, a longitudinal vertical section, taken in the plane of the line x x , fig. 1; and

Figure 3, a transverse vertical section, taken in the plane of the line y y , fig. 1.

Similar letters of reference indicate corresponding parts.

A, in the drawings, represents a case or box, made of wood, of suitable form and dimensions, and supported upon legs, B, one at each corner thereof.

C, the sound-board, secured in any suitable manner within the case A, in a plane between the bottom and top thereof.

This board has openings, D, at suitable points, to allow the escape of the sound, and, upon its under-

side, is stiffened by cross-bars, E, secured thereto by means of glue, or in any other suitable manner.

The several bars E extend in an angular direction across the board, with the two end ones made solid, but of less thickness than the space between the board and the bottom to the case, and the centre one of a skeleton-form or frame, forming a support to the board at its centre.

By the construction of the bars to the board, as above described, a full communication is permitted and established under the board for the sound. From the space between the bottom, A, and board C, the sound escapes through the openings D.

F, the bridges to the board, carrying the hitch-pins a and tuning-pins b for the strings G.

These bridges are made of iron, and are connected together and supported by rails, H, of the same material. These braces pass below the board C and support the bridges at different points, one rail being arranged under the rear ends of the bridges, one at the front-ends, and the other near their centres.

By these brace-rods H the bridges are braced and stiffened, and thus adapted for resisting the strain and tension of the strings of the instrument.

J, pedal-stand, secured to the under side of case A, and provided with pedal-feet, K, that, through suitable connecting-rods or bars, are arranged for operating upon the bars or rails L, properly located for dampening the sound of the strings, if so desired.

I claim as new, and desire to secure by Letters Patent—

1. The arrangement of the diagonal dampers L with relation to the bridges F, sound-board C, and strings G, of the dulcimer, as herein shown and described.

2. The construction of the bridges F, stiffening end-bars and central frame E, and the curved braces H beneath the sound-board C, all arranged as described, for the purpose specified.

WM. VOGEL.
